UNITED STATES PATENT OFFICE.

ALWIN VIETOR, OF WIESBADEN, GERMANY, ASSIGNOR TO THE FIRM OF GEORGES-MARIEN-BERGWERKS- & HÜTTEN-VEREIN A.-G., OF OSNABRÜCK, GERMANY.

RAILWAY-TIE.

1,163,717.

Specification of Letters Patent. Patented Dec. 14, 1915.

Application filed September 22, 1915. Serial No. 52,038.

To all whom it may concern:

Be it known that I, ALWIN VIETOR, a subject of the King of Prussia, German Emperor, residing in Wiesbaden, Germany, 5 doctor of philosophy and head engineer, have invented a new and useful Improvement in Railway-Ties, of which the following is a specification.

My invention relates to improvements in 10 cross-ties of rail-roads the trains of which run only in one direction on the tracks supported by the ties, and my primary object is to provide an inexpensive, strong and durable tie which shall be better capable than known ties of resisting the heavy trains, to 15 which railway-ties are subjected. To accomplish this object, I arrange the plane, connecting the under edges of the front and rear walls of the tie in such a manner obliquely, that it is nearly perpendicular to 20 the resulting force of vertical pressure and the horizontal strain of the running train working on the tie. In this position of the tie, the whole body of ballast, pressed by the 25 tie and supporting the tie will take up uniformly the horizontal strain to which the ties are subjected.

In the drawings several modifications of such a tie are shown.

30 Figure 1 shows in cross section an iron cross-tie according to my invention. Fig. 2 shows in cross-section a modification, having a rib for retaining the bed plate. Fig. 3 is a cross section of a further modification. 35 Figs. 4 and 5 show two other modifications of a tie having a cross-section of I-shape. Fig. 6 shows a tie of wood or concrete according to my invention.

The iron tie, shown in Fig. 1, consists of 40 the top a , the front wall b and the back wall c . The front wall b is shorter and the back wall c is longer than in the ties generally used, so that the plane connecting the under edges of the front- and the back wall lies 45 obliquely and is nearly perpendicular to the resulting force R of the vertical pressure D of the train and the horizontal strain S pro-

duced by the rolling train. The resistance of the ballast against the strains to which the tie is subjected, is therefore greater than 50 in ties, in which the front wall and the back wall have the same length.

The tie, shown in Fig. 2, is provided on the front edge of the top a^1 with a rib d for retaining a bed plate (not shown). A 55 rib on the back edge is not necessary, as the horizontal strain, produced by the rolling train, works only in one direction.

In the modification of the tie, shown in Fig. 3 the rib d^1 is provided with a forward 60 projection d^2 , and on the back edge of the top a^2 a similar projection d^3 is provided, directed backward. These projections may be engaged by well known clamping devices, connecting the rail with the bed plate and 65 the tie.

In Fig. 4 a tie is shown having an upper horizontal flat flange a^3 and an under horizontal flange g , both connected by the web f . The flange g is provided at its back edge 70 with a projection g^1 directed downwardly. A modification of this tie is shown in Fig. 5. The under flange g^4 is arranged obliquely so that it lies parallel to the plane, connecting the under edges of the walls b 75 and c of the ties shown in Figs. 1-3.

In Fig. 6 a tie a^5 of wood or concrete is shown, in which the front wall b^5 is shorter than the back wall c^5 so that the under wall h is oblique.

What I claim and desire to secure by Letters Patent is:

1. A railway tie having its bottom plane inclined substantially perpendicular to the resultant of the forces exerted on the tie. 85
2. A railway tie having its bottom plane inclined upwardly in the direction of the movement of the load thereon and substantially perpendicular to the resultant of the forces exerted on the tie. 90
3. A railway tie having a top wall, a short front wall depending therefrom, and a back wall depending a greater distance from the top wall than the front wall, the lower edges

of said depending walls being in a plane perpendicular to the resultant of the forces exerted on the top wall.

4. A railway tie consisting of a channel bar having a front depending side wall, and a rear side wall depending a greater distance than the front wall, the lower edges of said walls being in a plane perpendicular to the

resultant of the forces exerted on the top of the channel bar.

ALWIN VIËTOR.

Signed in the presence of the following two witnesses:

ELSE HOLLENWERK,
VICTOR DOER.
